UNITED STATES PATENT OFFICE.

WALTER R. HOPE, OF WILMINGTON, DELAWARE, ASSIGNOR TO THE E. I.
DU PONT DE NEMOURS POWDER COMPANY, OF WILMINGTON, DELA-
WARE, A CORPORATION OF NEW JERSEY.

MACHINE FOR MAKING TUBES FROM PULP, PAPER, OR SIMILAR MATERIAL.

No. 813,701.

Specification of Letters Patent.

Patented Feb. 27, 1906.

Application filed May 19, 1905. Serial No. 281,146.

To all whom it may concern:

Be it known that I, WALTER R. HOPE, a citizen of the United States, residing at Wilmington, county of Newcastle, and State of Delaware, have invented a new and useful Improvement in Machines for Making Tubes from Pulp, Paper, or Similar Material, of which the following is a full, clear, and exact description, reference being had to the accompanying drawings, which form a part of this specification.

The object of my invention is the production of a machine in which a plurality of mandrels or winders may be used upon which successively rolls or tubes may be wound and also to remove said rolls or tubes without removing the mandrels from the machine.

I will first describe the embodiment of my invention illustrated in the accompanying drawings and then point out the invention in the claims.

In the drawings, Figure 1 is a side or end elevation of the machine. Fig. 2 is an end view of a portion of Fig. 3 from the line 2 2 25 looking to the right. Fig. 3 is a front elevation of the entire machine. Fig. 4 is a view, partially in section, of a portion of the machine. Fig. 5 is a longitudinal section of another portion of the machine.

30 A is the frame of the machine, made up in the usual manner of a tub and housings, the latter forming the side walls of the tub.

B is the mold-roll rotating in the tub and supported in the housings. C is the couch-roll supported in the housings of the machine and contacting with the mold-roll. These rolls are driven by the gearing B' B² B³ B⁴ and pulley D on shaft E.

H is a shaft supported in the bearings N 40 N', mounted on the housings of the machine. Upon this shaft are mounted the spiders or supports T and T'. These spiders or supports support between them a plurality of winding-rolls or mandrels, each on a shaft X. Four winding-rolls are shown in the drawings equispaced around these spiders. As the construction of the spiders or supports for each winding-roll is the same, it is only necessary to describe one. The support T',

50 which I term the "pivot-support," is provided with a groove or slot T² for each winding-roll, in which rests a slide-block Y, free to move therein. Through this block passes

the end of shaft X of a winding-roll, such end being made square or rectangular. The 55 block is formed with a pivot K', which passes through an orifice in the shaft. Beyond the groove is the guide U', in which the end of the shaft rests. On the support T is the ring C², which prevents the shaft X at this end 60 from disengaging with the spider. The support T is provided with guides U for each winding-roll shaft similar to the guides U' of the support T'. Adjacent to each guide U by means of the pin A' is secured the latch 65 B', which engages with the shaft in the guide U and by means of the spring C' locks the shaft from moving in the guide. Each guide U and U' has a pocket in which a pin W, acted on by spring V, rests, the pins under the action 70 of the spring tending to move outward radially, thus contacting with the winding-roll shafts.

On the driving-shaft E is the eccentric F, connected, by means of the eccentric-rod I 75 and the pin J, to the crank G, mounted loosely upon the shaft H. On the end of crank G a pin K connects the crank with a pawl L, which pawl is adapted to operate the ratchet-disk M, securely keyed to the shaft H. This 80 pawl is provided with a pin J', which in certain portions of a cam R is adapted to be acted on by the cam and the pawl lifted free from the ratchet-disk. The cam R is carried by the boss formed with or connected to the 85 crank-arm O. A spiral spring Q loosely surrounds the shaft H and at one end is connected with the bearing of the shaft and the other end to the crank-arm O. The tendency of this spring is to move the cam R out of line of 90 pin J' on pawl L and allow the pawl to operate the ratchet-disk, and thus move the shaft H and turn the supports, bringing successively the winding-rolls in operative relation to the couch-roll. In order to prevent this 95 movement normally taking place and to allow it only to take place when a given winding-roll has received the required number of layers of pulp and then allow it to operate only sufficiently to move the full mandrel 100 away and another mandrel into position, I provide the following mechanism.

The crank-arm O at its free end is slotted and carries an adjustable pin S. This pin is in line with the squared end of the winding-roll shaft when the winding-roll is free from 105

pulp and in operative relation with the couch-roller, and therefore holds the crank against the action of the spring and the ratchet-disk in action, and no movement of the shaft 5 occurs. As, however, the winding-roll has layers of pulp placed upon it, its shaft moves vertically until it has passed above the pin S, when the pin is released and the cam-disk moved out of action, and the shaft is moved, 10 which causes the winding-roll just referred to to move away from the couch-roll and the next succeeding winder to approach it. In the movement of the last-mentioned roll its shaft end will strike the pin S on the crank- 15 arm O and move arm against the spring, moving the cam R again into action, stopping the movement of the shaft, and through the medium of the pin S locking the arm in that position.

20 In order to cause the winding-rolls to stop with certainty in the proper position with respect to the couch-roll, I employ the following mechanism: Fastened to the housing of the machine is the recess-bracket D', carrying the adjustable stop I', which stop is in line with the end of the shaft of the winding-roll and is adjustable, so as to be above the bottom of the shaft until the desired number of layers of pulp have been wound thereon.

25 E' is a spring-latch. As the empty winding-roll approaches the proper position with respect to the couch-roller its shaft, as before described, operates the crank-arm O. It also depresses and passes beyond the latch E', which 30 rises behind it. The forward movement of the winding-roll is stopped by striking the stop I'. The movement of the winding-roll in one direction is thus stopped, and its position is correctly determined by being held 35 between the stop I' and latch E'. When the winding-roll is covered with layers of pulp to the determined extent and its shaft is lifted above the stop I' and pin S, it is free to move under the action of the pawl and ratchet.

40 As may be seen from the hereinbefore 45 description, the winding-rolls are successively and automatically brought into and when covered the desired extent removed from operative position. The winding-roll covered with pulp moves into the position denoted by P, Fig. 2, and the tube may be stripped therefrom without removing the winding-roll in the following manner: The latch is moved from the shaft and the winding-roll turned on its pivotal connection with block Y, so that the end in support T will move free from the support, and the tube 55 may be stripped therefrom. The winding-roll is then swung back and the latch brought 60 again into holding position.

65 By my improved machine as the winding-rolls do not have to be removed from the machine to clear the tube therefrom I have with the plurality of winding-rolls I use practically a continuous operation.

Having now fully described my invention, what I claim, and desire to protect by Letters Patent, is—

1. In a machine of the character described, in combination, a couch-roll, a winding-roll adapted to receive the pulp or paper from the couch-roll, mechanism to move said roll away from operative relation with the couch-roll, said mechanism being normally inactive, and means whereby by reason of the winding-roll receiving a predetermined amount of pulp or paper, said mechanism becomes active. 70

2. In a machine of the character described, in combination, a couch-roll, a winding-roll adapted to receive the pulp or paper from the couch-roll, mechanism to move said roll away from operative relation with the couch-roll, said mechanism being normally inactive, means whereby, by reason of the winding-roll receiving a predetermined amount of 80 pulp or paper, said mechanism becomes active, and means operated by the winding-rolls to again render said mechanism inactive.

3. In a machine of the character described, in combination, a couch-roll, a plurality of 90 winding-rolls adapted to be moved successively in operative position with reference to the couch-roll, mechanism, normally inactive, to move said winding-rolls, means adapted to render said mechanism active by reason of the active winding-roll receiving a predetermined amount of pulp or paper. 95

4. In a machine of the character described, in combination, a couch-roll, a plurality of 100 winding-rolls adapted to be moved successively in operative position with reference to the couch-roll, mechanism, normally inactive, to move said winding-rolls, means adapted to render said mechanism active by reason of the active winding-roll receiving a 105 predetermined amount of pulp or paper, and means operated by the winding-rolls to again render said mechanism inactive.

5. In a machine of the character described, in combination, a couch-roll, a plurality of 110 winding-rolls, means to move said winding-rolls one by one into operative position with respect to the couch-roll, and locking mechanism adapted to directly hold the operative winding-roll from movement beyond operative 115 position with respect to the couch-roll.

6. In a machine of the character described, in combination, a couch-roll, a plurality of 120 winding-rolls, means to move said winding-rolls one by one into operative position with respect to the couch-roll, and locking mechanism adapted to directly hold the operative winding-roll from movement in either direction from operative position with respect to the couch-roll. 125

7. In a machine of the character described, in combination, a couch-roll, a plurality of winding-rolls, means to move said winding-rolls one by one into operative position with respect to the couch-roll, and locking mech- 130

anism adapted to hold the operative winding-roll from movement beyond operative position with respect to the couch-roll, said winding-roll being released from said locking means by reason of a predetermined amount of pulp or paper being laid upon said roll.

8. In a machine of the character described, in combination, a couch-roll, a plurality of winding-rolls, means to move said rolls one by one into operative position with respect to said couch-roll, a locking device adjacent to said couch-roll in line of movement of the winding-rolls and adapted to yield in the movement of the winding-roll toward the operative position with respect to the couch-roll and allow said roll to pass beyond said locking device.

9. In a machine of the character described, in combination, a couch-roll, a plurality of winding-rolls, means to move said rolls one by one into operative position with respect to the couch-roll, each winding-roll being supported so as to be independently vertically movable, and a stop in line of movement of said winding-rolls in one vertical position of said rolls, and out of line at another vertical position of said rolls.

10. In a machine of the character described, in combination, a couch-roll, winding-rolls, a support or supports in which said rolls are independently secured, a shaft for operating said supports, a rack and pawl for operating said shaft, a cam adapted in one position to render said pawl inoperative, and means during the movement of said winding-rolls to move and hold said cam in said position, and means to release said cam when the operative winding-roll receives a predetermined amount of pulp or paper.

11. In a machine of the character described, in combination, a couch-roll, winding-rolls, a support or supports in which said rolls are independently secured, a shaft for operating said supports, means to operate said shaft, a device adapted to render said means inactive, means, during the movement of the winding-roll, to throw said device into action, and means to throw said device out of action when the operative winding-roll receives a predetermined amount of pulp or paper.

12. In a machine of the character described, in combination, a couch-roll, winding-rolls, a support or supports in which said rolls are independently secured, a shaft for operating said supports, a rack and pawl for operating said shaft, a cam adapted in one position to render said pawl inoperative, a spring tending to hold said cam in the other position, a lever, connected with said cam, in line of movement of the winding-rolls and adapted, when struck, to move said cam to the first-mentioned position.

13. In a machine of the character described, in combination, a couch-roll, wind-

ing-rolls, a support or supports in which said rolls are independently secured, a shaft for operating said supports, a rack and pawl for operating said shaft, a cam adapted in one position to render said pawl inoperative, a spring tending to hold said cam in the other position, a lever, connected with said cam, in line of movement of the winding-rolls and adapted, when struck, to move said cam to the first-mentioned position, and a stop, adapted to hold it in said position, controlled by the winding-roll in operative relation with the couch-roll.

14. In a machine of the character described, in combination, a couch-roll, winding-rolls, a support or supports in which said rolls are independently secured, a shaft for operating said supports, a rack and pawl for operating said shaft, a cam adapted in one position to render said pawl inoperative, a spring tending to hold said cam in the other position, a lever, connected with said cam, in line of movement of the winding-rolls and adapted, when struck, to move said cam to the first-mentioned position, a stop, adapted to hold it in said position, controlled by the winding-roll in operative relation with the couch-roll, and means to release said stop when said winding-roll receives a predetermined amount of pulp or paper.

15. In a machine of the character described, in combination, a couch-roll, winding-rolls, a support or supports in which said rolls are independently secured, a shaft for operating said supports, a rack and pawl for operating said shaft, a cam adapted in one position to render said pawl inoperative, a spring tending to hold said cam in the other position, a lever, connected with said cam, in line of movement of the winding-rolls and adapted, when struck, to move said cam to the first-mentioned position, a stop adapted to hold it in said position, said winding-rolls being supported so as to be vertically movable, said stop being controlled by the winding-roll in operative relation with the couch-roll in one vertical position and released in another vertical position.

16. In a machine of the character described, in combination, a winding-roll, supports for the opposite ends of said roll, said roll being pivotally secured in one support and adapted to move free from the other support.

17. In a machine of the character described, in combination, a winding-roll, supports for the opposite ends of said roll, said roll being pivotally secured in one support and adapted to move free from the other support, and means to normally restrain the movement of the roll at said last-mentioned end.

18. In a machine of the character described, in combination, a winding-roll, a shaft therefor projecting beyond the roll ends,

a support for each end of said shaft, said shaft being pivoted in one support and adapted to move free from the other support.

19. In a machine of the character described, in combination, a winding-roll a shaft therefor projecting beyond the roll ends, a support for each end of said shaft, said shaft being pivoted in one support and adapted to move free from the other support, and means to normally restrain the free movement of said shaft.

20. In a machine of the character described, in combination, a winding-roll, a shaft therefor, projecting beyond the ends of said roll, a frame having a slotted and cut-away portion, a block in said slotted portion, said shaft being pivotally connected to said block, a support for the opposite end of the shaft on which the shaft is free to move.

21. In a machine of the character described, in combination, a winding-roll, a shaft therefor, projecting beyond the ends of said roll, a frame having a slotted and cut-

away portion, a block in said slotted portion, said shaft being pivotally connected to said block, a stop limiting the movement of said shaft on its pivot in one direction, a support for the opposite end of the shaft in which the shaft is free to move.

22. In a machine of the character described, in combination, a winding-roll, a shaft therefor, projecting beyond the ends of said roll, a frame having a slotted and cut-away portion, a block in said slotted portion, said shaft being pivotally connected to said block, a support for the opposite end of the shaft on which the shaft is free to move, and a latch for limiting the free movement of said shaft.

In testimony of which invention I have hereunto set my hand, at Wilmington, Delaware, on this 11th day of May, 1905

WALTER R. HOPE.
